UNITED STATES PATENT OFFICE.

WILLIAM E. PETERS, OF ATHENS, OHIO.

TELEPHONE-RECEIVER.

No. 911,438.

Specification of Letters Patent.

Patented Feb. 2, 1909.

Application filed December 24, 1907. Serial No. 407,910.

To all whom it may concern:

Be it known that I, WILLIAM E. PETERS, a citizen of the United States, residing at Athens, in the county of Athens and State of Ohio, have invented certain new and useful Improvements in Telephone-receivers; and I do declare the following to be a full, clear, and exact description of the invention, such as will enable others skilled in the art to 10 which it appertains to make and use the same.

This invention relates to new and useful improvements in telephone receivers.

The principal object of the invention is 15 the production of a simple and economical receiver cap, through the use of which the pressure exerted upon the ear will be transferred to the head, so that bruising of the ear and the attendant annoyances resulting 20 therefrom may be obviated.

In the accompanying drawings:—Figure 1 is a view illustrating the application of the invention to a head band receiver of any common type. Fig. 2 is a central cross sectional 25 view of the invention on an enlarged scale.

Referring to the drawings, which are for 30 illustrative purposes only, and, therefore, not drawn to scale, the numeral 1 indicates the body of the receiver, and 2 the improved 35 cap, which is designed to be attached to, or to take the place of the various forms of caps now in use, and which constitutes the invention. This cap comprises an annular body 3 of hard rubber or other suitable material, 35 which is of sufficient size to inclose the ear of the operator, or user.

In carrying out the invention, a diaphragm 40 or support 4 formed with a relatively large central opening 5 is arranged in the annular body 3 of the cap at the desired distance from the inner edge thereof, and a corresponding cushioning ring 6, of soft rubber, felt, heavy cloth or like material arranged over the inner face of the diaphragm, said 45 ring serving as a bed for the inner end of the receiver body and is a means for excluding outside noises.

The diaphragm 4 is spaced from one edge 50 of the cap body 3 to provide the latter with a rim or flange 7 which is interiorly threaded to screw upon one end of the receiver body. A cushioning ring 8 of soft rubber, felt or other like material is also arranged in the cap body 3 with its outer edge projecting slightly beyond 55 said edge of the latter in order to bear

against the side of the head and face to protect the same from becoming bruised or irritated and the attendant annoyances resulting therefrom. Said cushioning ring 8, which is of straight form in cross section, is retained in position by a clamping band 9 of hard rubber or the like, formed at its inner edge with an annular outstanding flange 10 which fits against the inner surface of the cap body to retain the clamping band in detachable position.

If found desirable, instead of relying on the pressure exerted upon opposite faces of the ring 8 for securing it in position, it may be fastened in any suitable manner to the fastening ring or band 9.

From the construction defined and illustrated, it will be seen that a cap constructed in accordance with the invention may be readily and easily applied or removed from the body of the receiver, and by its use liability of the ear of the operator, or user, becoming bruised or irritated, and the attendant annoyances resulting therefrom will be guarded against. It has also been found that by employing a cap of the construction shown, the pressure of the head band upon the side of the head and face is greatly modified. It may be also seen that by employing the form of cap shown outside noises 85 are positively excluded, and the operator, or user, not so liable to become confused when receiving a message.

Having described my invention, I claim;

1. A telephone receiver comprising a body and a cap member, the latter comprising an annular body adapted to strew upon the receiver body, a diaphragm having a relatively large central opening arranged within the body member, said diaphragm being spaced a slight distance from one edge of the body member, a cushioning ring corresponding with and arranged over the diaphragm, a second cushioning ring of soft flexible material arranged at the edge of the body member opposite the diaphragm, the outer edge of said ring projecting beyond said edge of the body member, and means for securing said ring in position.

2. A telephone receiver comprising a receiver body and a cap, the latter embodying an annular body adapted to screw upon one end of the receiver body, a cushioning ring of straight form in cross section arranged in the cap body with one edge projecting

beyond the same, and a clamping band arranged in the receiver cap to hold said cushioning ring in position said clamping band being formed with an annular outstanding
5 flange to engage the inner surface of the cap body and the inner edge of the cushioning ring.

In testimony whereof I have hereunto set my hand in presence of two subscribing witnesses.

WILLIAM E. PETERS.
